FEED CONTROL MECHANISM

Nels T. Holmbeck, Chicago, Ill.

Application October 8, 1942, Serial No. 461,290

8 Claims. (Cl. 164—22)

My invention relates to a feed control mechanism adapted particularly for accurately controlling the feed of stock, such as a metal strip or band, to the cooperating members of die sets, punching assemblies, or the like.

My invention concerns particularly improved operation and control of stock feed mechanism which is permanently attached to and forms an integral part of a die set assembly, as for example in the arrangement disclosed in Dicker-
man Patent No. 1,968,479, dated July 31, 1934. In this type of feeding arrangement, a stationary gripper unit and a reciprocating gripper unit co-operate with the movement of the punch element of a die set to shift the stock band periodically the required feed distance into the die set and to hold it while the die operations are being performed. However, it has been found that, in feed structures of this type, there may be very slight overfeed, or underfeed, for each feeding operation, and although such error may be very slight for each feed movement, the error will be so multiplied during a period of operation of the die set that the incorrect feeding will result in imperfect die formation of the object to be formed out of the stock band.

The important object of my invention is therefore to provide simple means for correcting each feed movement of the stock band before operation of the die set to work on the band. This I preferably accomplish by effecting release of both gripper units from the stock band just prior to final closing of the die elements and by providing an aligning member on the punch element for engagement with the freed band to shift it into proper position over the die element for final movement of the punch element into forming engagement with the stock band.

The purposes and advantages of my invention will be clearly understood from the structure shown on the drawings, in which:

Figure 1 is a side elevation of the inlet end of a die set and the feed mechanism secured thereto;

Figure 2 is a plan view of the feed mechanism;

Figure 3 is an enlarged section on plane III—III of Figure 2, showing the position of the reciprocating gripper unit after a feeding operation;

Figure 4 is a similar section showing the gripper unit about to engage the stock band for feeding thereof;

Figure 5 is a section on plane V—V Figures 2 and 3;

Figure 6 is a perspective view of one of the

raise bars which function to release the gripper units from the band; and

Figure 7 is an enlarged cross-sectional view of the upper and lower feed rollers of the gripper unit to show the clutch mechanism for permitting rotation of the rolls in only one direction.

The frame of the feed mechanism comprises inner and outer cross walls 10 and 11, and front and rear side walls 12 and 13. Adjacent to the outer cross wall 11 is the stationary gripper assembly A. This assembly comprises the shaft 14 extending between and secured to the side walls 12 and 13 by caps 15 through which extend set screws 16 for holding the shaft against rotation. Extending between the side walls 12 and 13 and mounted on the shaft 14 is the lower feed roll 17.

At their upper ends the side walls 12 and 13 have the rectangular slots 18 respectively for the rectangular bearing blocks 19 which receive the ends of a shaft 20 on which is mounted the upper gripper roll 21 which extends between the side walls 12 and 13. Set screws 22 hold the shaft against rotation in the bearing blocks.

Extending between the side walls 12 and 13 and across the upper ends of the slots 18 is a plate 23 which is detachably secured to the walls as by screws 24. This plate has upwardly extending opposed walls 25 and 26 thereon between which is located a pressure bar 27 which, at each end, has a threaded stud 28 extending therethrough in alignment with the corresponding bearing block 19. The threaded studs at their lower ends terminate in abutment heads 29 between which and the bearing blocks 19 springs 30 are interposed.

Between the side walls 25 and 26 above the pressure bar, a cam lever 31 is secured to a fulcrum pin 32 journalled in the side walls, the cam lever having the cam head 33 which, upon downward swing of the lever, will force the pressure bar 27 downwardly for compression of the springs 30 and corresponding pressure against the shaft 20 to hold the upper roll 21 in pressure engagement with the lower roll 17.

The reciprocating gripper unit B comprises the side walls 34 and 35 connected at their lower ends by cross bars 36 and these side walls are secured to front and rear guide or carriage frames 37 and 38, as by bolts 39. These guide frames 37 and 38 have guide channels 40 and 41, respectively, therethrough for receiving the inner guide portions 12' and 13' of the side walls 12 and 13.

The side walls 34 and 35 at their lower ends receive the shaft 42 for the lower gripper roll 43,

the shaft being locked against rotation by set screws 44. In their upper ends the side walls 34 and 35 have the rectangular slots 45 for the bearing blocks 46 which receive the shaft 47 for the upper gripper roll 48, set screws 49 holding the shaft against rotation in the bearing block.

A plate 50 is detachably secured by screws 51 to the side walls 34 and 35 over the tops of the slots 45, and between the side walls 52 and 53 on the plate is the pressure bar 54 having threaded studs 55 therethrough at its ends terminating in heads 56 between which and the respective blocks 46 are located the springs 57. The cam lever 58 is secured to the fulcrum pin 59 journalled in the side walls 52 and 53 and upon downward swing of the lever the cam head 60 will shift the pressure bar downwardly for pressure exertion of the spring to hold the upper gripper roll 48 for pressure engagement against the lower roll 43. By virtue of the threaded engagement of the studs 55 in the pressure bar 54 (Figure 5), and the threaded engagement of the studs 28 in the pressure bar of the gripper unit A (Figure 1), the desired pressure engagement of the upper gripper rolls with the respective lower gripper rolls can be obtained. After setting of the studs they are held in adjusted position by lock nuts 61.

The front and rear guide frames 37 and 38 for the reciprocating gripper unit B have abutment ears 62 and 63 thereon to which rods 64 and 65 are rigidly secured and to extend therefrom through passageways 66 in the ears 67 and 68 on the outer end wall 11. Between the opposed ears, the rods support compression springs 69 and 70, and the outer ends of the rods being threaded to receive adjusting and lock nuts 71. The springs tend to hold the gripper unit B in its inner position with the nuts 71 abutting the ears 67 and 68, and by means of the nuts 71 the feed travel of the unit B is determined.

The stock band S extends through the feed mechanism between the upper and lower rolls of the gripper units, the rolls of each unit having the central portion 72 of increased diameter and of less width than the band, the end portions 73 of the rolls being of lesser diameter so that the pressure of the springs against the supporting blocks for the shafts of the upper rolls will exert pressure against the band to hold it against the lower rolls.

Referring to Figure 7, each of the rolls is permitted to rotate only in one direction on its supporting shaft and is locked against rotation in the opposite direction. Any suitable locking or clutch means may be provided. As shown, clutch balls 74, urged by springs 75, will lock each upper roll against counterclockwise rotation but will permit clockwise rotation thereof, while the clutch mechanism in the lower rolls lock them against clockwise rotation but permit counterclockwise rotation. Thus, after a feed of the stock band, the rollers on the unit A will hold the band against reverse movement, but the rolls on the unit B will roll along the band as the supporting carriage for the rolls is shifted outwardly, and then upon inward or feeding movement of the unit B, its rolls will clamp the band for feed thereof during inward movement of the carriage, the rollers of the unit A being then free to rotate.

Adjustably secured to the end wall 11 of the feeder structure, are arms 76 journalling opposed guide rollers or spools 77 between which the incoming stock band S passes. On the inner end wall 10 similar guide rollers or spools 78 are journalled between which the band travels, 75

these spools tending to hold the band aligned on its passageway through the feeder units. To further guide the band and to hold it aligned with the gripper rolls, guide member 79 and 80 are provided. As shown, each guide member comprises upper and lower plates 81 and 82 separated along their outer portions by a spacer plate 83, the upper and lower plates along their inner portions receiving between them the edge portions 10 of the stock band, the spacer plates forming guides engaged by the edges of the stock band. These guide structures are secured at their ends to the end walls 10 and 11 as by screws 84. As indicated at 85, the guide members are cut away at their inner portions sufficiently to provide clearance for engagement with the band of the center portions 72 of the rolls 17 and 21, and as indicated at 86, the guide members are cut out along their inner portions to provide clearance for engagement with the band of the center portions 72 of the rolls 43 and 48 as the unit B is reciprocated.

Referring to Figures 1 and 3, the die block 87 of a die set supports the various die structures D, and the punch block 88 supports the various punch structures P. The feed structure is secured to a supporting block 89 on the die block by means of screws 90 passing through the end wall 10 and threading into the block 89. The die set with the feed attachment thereon is placed on a punch press bed for cooperation of the punch press ram with the punch block 88 in a manner well understood in the art.

At the upper inner corners of the guide frames 37 and 38 for the feed unit B are journalled cam rollers 91 and 92 for engagement by cam plates 93 and 94 secured to and depending from the punch block 88. These cam plates are of rectangular cross section and each presents at its lower end the diagonally extending cam surface 95 terminating in the vertical surface 96 at the inner edge of the plates, the width of the plates at the surface 96 being equal to the distance of the desired feed of the stock band. Above the surface 96 the cam plates have the vertical surfaces 97 offset inwardly from the surfaces 96 a short distance. As shown on Figure 1, when the punch block 88 is in its upper position, the lower forward ends of the inclined cam surfaces 95 are in engagement with the cam rollers so that, upon downward movement of the punch block, the feed unit B will be shifted outwardly until the vertical surfaces 96 receive the cam rollers. Such outward movement of the unit B is resisted by the springs 69 and 70. During such outward movement of the unit B, the stock band will be held against outward movement by the rolls of the unit A which are locked against rotational movement, the rolls of the unit B being however free to roll along the stock band. While the rollers are being engaged by the vertical surfaces 96, the punch block 88 is moved down sufficiently for punching or forming work on the band. As the punch block 88 is then moved upwardly the vertical surfaces 96 will leave the cam rollers and the cam rollers will come into engagement with the inclined cam surfaces 95 along which they will travel by the pressure of the springs 69 and 70 until the unit B is restored to its inner position. During such inward movement of the unit B, its rolls will be locked against rotation and will grip the stock band to feed it into the die set, the rolls on the unit A being then free to rotate. After the feed operation both sets of rolls will be locked against rotation to prevent

outward movement of the band from its fed-in position.

Although great precision is employed in making and assembling the feed structure, very slight overfeed or underfeed may occur which, for a single feed operation, may not be material, but which, when multiplied after a period of operation of the die and feed structure, may cause error in the formation of the band by the die structures. I have therefore provided simple and efficient means for compensating for any feed errors and assuring accurate and correct positioning of the band in the die structure before the punch or other forming members on the punch block come into engagement with the band and the die structures on the die block. This I accomplish by effecting release of the upper rolls of the feed units from the band at the end of the outward movement of the unit B, and providing aligning means on the punch block for cooperation with the released band to shift it into its proper position in the die set. As shown on Figure 1 I mount an aligning pin 98 in the punch block 88, which pin has a tapered end, and in the die structure adjacent to the feed mechanism I provide a passageway 99 for the aligning pin. In advance of the aligning pin, the punch block carries a punch pin 100 for cooperating with a die passageway 101 to punch out the stock band to provide pilot holes 102 for passage of the aligning pin into the passageway 99, so that the tapered end of the aligning pin may engage with the band edges around the holes 102 to shift the band, if necessary, to bring the holes 102 into alignment with the passageway 99 and thereby set the band in proper position for die operation.

The mechanism for releasing the upper rolls from the band for operation of the aligning pin, is best shown on Figures 2, 3, 4 and 6. The releasing mechanism is in the form of raise bars 103, one of such bars being shown in perspective in Figure 6. The two bars are supported from the guide structures 79 and 80 in alignment with the cylindrical end portions 73 of the rolls in the units A and B, the ends 104 of the bars being of a height to extend between these end portions of the rolls when the upper rolls are clamped down against the stock band. The middle portions 105 of the bars are received in supporting and guide brackets 108 secured to and extending from the respective guide structures 79 and 80, with the outer end portions 104 of the bars extending between the outer portions 73 of the rolls of the unit A. Between its inner portion and its outer portion each bar has upwardly extending portions 106, the approaches 107 to these portions 106 being inclined, as clearly shown on Figure 6.

When the punch block 88 is in its upper position and the unit B is in its inner position as shown on Figures 1, 2 and 3, the rolls of the unit B are displaced from the inner ends of the raise bars 103. When the unit B is shifted outwardly by the cam plates 93 and 94 upon downward movement of the punch block, the spaces between the outer portions 73 of the rolls on unit B will receive the outer ends 104 of the raise bars, and when the cam rollers 91 and 92 are in engagement with the vertical surfaces 96 on the cam plates, the inclined surfaces 107 at the inner ends of the raise bars will be engaged by the outer portions 73 on the upper roll of the unit B, and the inclined surfaces 107 at the outer ends of the raise bars will be in engagement with the outer portions 73 of the upper roll of the unit

A. Now, as the punch head is moved down further to engage the surfaces 97 of the cam plates with the cam rollers 91 and 92, the resulting final movement of the unit B toward the unit A 5 will cause the inclined surfaces 107 to wedge the upper rolls of the units upwardly against the pressure of their pressure bars to release the rolls from the stock band. This released position of the upper rolls is maintained while the 10 vertical surfaces 97 on the cam plates remain in engagement with the cam rollers, and while the stock band is thus released, the aligning pin 98 will pass with its tapered end through the hole 102 in the band and will center this hole 15 with the passageway 99 so that, if there was any error in the feeding of the band by the feed mechanism, such error will be compensated for and the band shifted into the proper position for engagement by the forming members on the 20 punch block, the operation of the aligning pin taking place just before the punch pin 100 and other punch or forming members on the punch block come into engagement with the band and the cooperating die elements on the die block 87. The punch pin 100 then punches the hole in the 25 stock band for cooperation with the aligning pin 98 after the next feed operation of the feed mechanism. Such feed takes place as the cam plates are withdrawn from the cam rollers as the punch block moves upwardly. As the punch block starts to move upwardly, the aligning pin 98 will remain in the hole 102 until the vertical cam surfaces 97 on the cam plates are withdrawn 30 from the cam rollers on the unit B, the movement of the cam rollers from the surfaces 97 to the vertical surfaces 96 permitting the outer portions 73 of the upper roll of the unit B to leave the inclines 107 at the inner ends of raise bars so that the bars are free to be shifted inwardly 35 40 by the pressure of the upper roll of the unit A against the outer inclines 107 on the bars, the pressure bars on the units A and B being then free to reset the upper rolls against the stock band for gripping of the band between the rolls 45 of the unit B so that, as the cam rolls on the unit B come into engagement with the inclined cam surfaces 95 on the cam plates, the springs 69 and 70 may shift the unit B to its inner position and to feed the clamped band into the die set. On the raise bars, the spaces between the 50 projections 106 are sufficiently longer than the width of the supporting brackets 108 so that the bars may have sufficient longitudinal movement to be shifted into wedging engagement with the 55 upper rolls during the final outward movement of the unit B and to be freed from the rolls during inward or feeding movement of the unit B.

When a new stock band is to be fed into the structure, the punch head 88 is brought down 60 until the surfaces 97 on the cam plates will just come into engagement with the cam rollers on the unit B and before the punch pin 100 reaches its cooperating die element. The upper rolls of the units A and B being then raised, the end of 65 the stock band can be fed in past the die passageway 101 but short of the passageway 99 for the pin 98. Then upon final downward movement of the punch block, the punch pin will punch in the band a hole 102, shown in dotted lines on Figure 2, and when the punch block is again raised and the unit B is shifted inwardly 70 for feeding the band, this hole 102 will be brought into registration with the die passageway 99 for aligning cooperation with the pin 98 when the 75 punch block is again brought down for outward

movement of the unit B and raising of the upper rolls of the units from the band.

I thus provide simple and efficient means in connection with feed mechanisms of the type described which will compensate for any feed errors and assure accurate alignment of the stock band in the die set before any die operation on the band. I do not however desire to be limited to the exact structure, arrangement and operation shown and described as changes and modification may be made without departing from the scope of the invention.

I claim as follows:

1. In a die set, cam means on one of the co-operating and relatively movable members of the set, a supporting frame secured to and extending longitudinally from the other of said members, a carriage movably mounted on said supporting frame and having a part for engagement by said cam means, stock gripper means on said carriage free to move relative to the stock upon outward movement of the carriage by said cam means, spring means for shifting said carriage inwardly upon release thereof from said cam means, said gripper means during movement of the carriage by said spring means being effective to grip the stock whereby the stock is fed into the die set, means effective during the final movement of said carriage by said cam means for entirely disconnecting said gripper means from the stock for free longitudinal movement thereof in either direction, and means on the die set for cooperating with the released stock to correct for any overfeed or underfeed thereof and to accurately align the stock in the die set just before the stock is worked on by the die set members.

2. In a die set, cam means on one of the co-operating and relatively movable members of the set, a supporting frame secured to and extending longitudinally from the other of said members, a carriage movably mounted on said supporting frame and having a part for engagement by said cam means, stock gripper means on said carriage free to move relative to the stock upon outward movement of the carriage by said cam means, spring means for shifting said carriage inwardly upon release thereof from said cam means, said gripper means during movement of the carriage by said spring means being effective to grip the stock whereby the stock is fed into the die set, means effective during the final movement of said carriage by said cam means for entirely disconnecting said gripper means from the stock for free longitudinal movement thereof in either direction, means on the die set for punching pilot holes in the stock, and alining means on said die set cooperable with said pilot holes while the stock is free of the gripper means for compensating for any overfeed or underfeed by the gripper means and to properly align the stock in the die set before the stock is worked on by the die set members.

3. In a die set a supporting frame secured to and extending outwardly from one of the die set members, a gripper unit movable on said frame and having gripping means for gripping stock to be fed into the die set, cam means on the other member of the die set effective during closure movement of the die set members to shift said gripper unit outwardly for gripping engagement with the stock, said cam means being further effective to overshift said unit outwardly during the end part of closure movement of said die members, means effective during such

overshift of said unit for entirely releasing the gripping means from the stock for free longitudinal movement thereof in either direction, and means effective during the fore part of the final movement of said die members toward each other for engaging with the released stock to effect movement thereof to correct any overfeed or underfeed thereof by the gripper unit and to accurately align the stock in the die set members.

10 4. A die set having stock feed mechanism thereon in the form of a permanent attachment, means controlled by the closing and opening movements of the die set members for effecting operation of the feed mechanism to feed stock

15 into the die set, means effective just before final closure movement of the die set members for entirely releasing the feed mechanism from the stock for free longitudinal movement thereof in either direction, and means on the die set members for cooperation with the released stock to correct any overfeed or underfeed of the feed mechanism and to correctly position the stock before engagement therewith of forming structure on the die set members.

20 5. A die set comprising members movable to open or closed position, feed mechanism forming a part of the die set, means controlled by the closing and opening movement of the die set members for controlling the feed mechanism to feed stock between the die set members, punch

25 means for the die set members for punching pilot holes in the stock during closure movement of the members, means effective just before final closure movement of the die set members for effecting entire release of the feed mechanism from the stock for free longitudinal movement thereof in either direction, an aligning pin on one of the die set members and a passageway therefor in the other die set member, said pin

30 just before final closing movement of the die set members being projected through one of the pilot holes and into said passageway for shifting the stock after release of the feeding mechanism therefrom whereby to correct for any overfeed or underfeed of the stock by the feeding mechanism and to accurately align the stock between the die set members before said members are finally moved to closed position.

35 6. A die assembly comprising a die block element and a punch block element, a supporting frame extending from the die block element, a stationary gripper unit on said supporting frame and a feeding gripper unit reciprocable on said frame, cam means on said punch block member

40 engageable with said reciprocating unit to shift it outwardly upon closure movement of the die block and punch block members, spring means for shifting the reciprocating unit inwardly during opening movement of the die and punch block

45 assemblies, an upper and a lower gripper roll for each unit and spring means tending to urge said rolls together for clamping a stock band to be fed by the unit, said rolls being adapted to rotate in only one direction whereby the rolls on the stationary unit will hold the stock band against outward movement and the rolls on the reciprocating unit may roll along the band during outward movement of the unit and to grip the band during inward movement of the unit

50 for feed of the band, means effective during the final outward movement of said reciprocating unit for entirely releasing the gripper rolls from the stock band for free longitudinal movement of the band in either direction, and cooperating means on said die and punch block mem-

bers for engagement with the released stock band to shift it for correction of any overfeed or underfeed by the feeding mechanism and to accurately align it for working engagement by die and punch structure on said die and punch block members.

7. A die assembly comprising a die block element and a punch block element, a supporting frame extending from the die block element, a stationary gripper unit on said supporting frame and a feeding gripper unit reciprocable on said frame, cam means on said punch block member engageable with said reciprocating unit to shift it outwardly upon closure movement of the die block and punch block members, spring means for shifting the reciprocating unit inwardly during opening movement of the die and punch block assemblies, an upper and a lower gripper roll for each unit and spring means tending to urge said rolls together for clamping a stock band to be fed by the unit, said rolls being adapted to rotate in only one direction whereby the rolls on the stationary unit will hold the stock band against outward movement and the rolls on the reciprocating unit may roll along the band during outward movement of the unit and to grip the band during inward movement of the unit for feed of the band, means effective during the final outward movement of said reciprocating unit for entirely disengaging the gripper rolls from the stock band to release the band for longitudinal movement in either direction, a punch pin on the punch block member for punching pilot holes in the stock band, a tapered aligning pin on the punch block member engageable in one of the pilot holes while said stock band is released and before engagement with the stock band of the punching pin for shifting the stock to correct any overfeed or underfeed by the feeding mechanism to properly align the stock between the die and punch block members.

8. A die assembly comprising a die block element and a punch block element, a supporting frame secured to and extending outwardly from the die block element, a stationary gripper unit on said supporting frame and a reciprocating

gripper unit on said frame, upper and lower gripper rolls for each unit between which a stock band is to be shifted for feeding between the die and punch block elements, yieldable clamping means engaging the upper rolls of the units for clamping of the stock band, the rolls of said units being capable of rotating in only one direction whereby the rolls of the stationary unit will hold the stock band against outward movement and the rolls on the reciprocating unit may roll along the band during outward movement of the unit but will grip the band during inward movement of the unit, cam means on said punch block element having a cam surface engageable with the reciprocating unit to shift it outwardly along the stock band while the band is being held by the stationary unit, spring means for returning said reciprocating unit inwardly when said cam surface is being withdrawn therefrom, the movement of said reciprocating unit by said cam surface being equal to the desired distance of feed of the stock band, another cam surface on said cam means operative after movement of said reciprocating unit by said first mentioned cam surface to effect a slight further outward movement of said reciprocating unit, raise bars longitudinally movable on said supporting frame and having inclined surfaces at their ends for engagement with the upper rolls of the units to raise them entirely away from the stock band during such final outward movement of the reciprocating unit whereby the stock band will be entirely released from the units, a punch pin on said punch block element for punching pilot holes in the stock band, a tapered aligning pin on said punch block element spaced from said pilot punch pin a distance corresponding to the desired feed distance of the stock band, said aligning pin being engageable in a pilot hole in the stock band while said stock band is held released from the feeder units for shifting of the stock band to correct any underfeed or overfeed by the shifting unit whereby to properly align the band for punching thereof by the pilot punch pin.

NELS T. HOLMBECK.
